UNITED STATES PATENT OFFICE.

JAMES J. HENNESSY, OF NEW YORK, N. Y.

LUBRICATOR.

Application filed July 27, 1922. Serial No. 578,019.

My invention relates to lubricators such as are especially adapted for use in railroad rolling stock journal boxes, and consists in a pumping means and a conduit or passage 5 for the pumped lubricant to the surface of the journal to be lubricated. In Patent No. 1,265,198, issued to me May 7, 1918, I disclose a lubricator in which the lubricant is fed to the journal by the inertia of members 10 rolling on the bottom of the lubricant reservoir.

One object of my present invention is to improve upon this inertia operating means by providing a pump operated by inertia, 15 thereby securing a more positive and efficient supply of lubricant to the wearing surface.

Another object of my invention is to provide a flexible conduit for the lubricant from the surface of supply to the surface to be lubricated and to deliver the lubricant uniformly 20 to a substantial area of the journal independently of variations in the position of the journal in the journal box.

In the accompanying drawings which illustrate a selected embodiment of my invention,—

Figure 1 is a longitudinal section through my lubricator and showing a portion of a journal to which it is applied.

Figure 2 is a transverse section through the lubricator and journal.

The body 1 of the lubricator comprises a reservoir which is adapted to be seated in the journal box (not shown) and is provided 35 with an integral pump cylinder 2 and pump delivery barrel 3, the former extending horizontally and located near the bottom of the reservoir, the latter extending vertically from the inner end of the pump cylinder to a point well above the height of the lubricant in the reservoir. A ball 4 serves as a check 40 valve in barrel 3 and the lubricant is forced through cylinder 2 past ball 4 by means of a plunger 5, the construction and operation of which is detailed in my copending application Serial No. 578,018. The plunger is preferably operated by a reciprocating 45 movement of a block 6 of wood or other material adapted to float upon the lubricant in the reservoir and of an area which permits 50 to have substantial movement lengthwise of the reservoir.

Block 6 is provided with a central opening 7 which fits over barrel 3 and prevents limitation 55 of the movement of the block. Block 6 is connected to plunger 5 by a stem 8 rigidly

attached to plunger 5 and having an elongated bearing in block 6 upon which the block may slide vertically when it rises and falls with the surface of the lubricant. There is no free play between the block and stem in a horizontal direction. Consequently, whenever the car or journal box is shifted lengthwise of the journal axis, the inertia of the block will cause the latter to move relative to the pump cylinder and withdraw the plunger somewhat from the cylinder or force it further into the same.

Whenever the former action takes place, the amount of lubricant in front of the plunger is increased and whenever the latter action takes place, a portion of this lubricant is forced up into barrel 3. The upper end of barrel 3 is fitted with a member 9 having a circular opening in its side 10. A hollow ball 11 is positioned in member 9 and seated against the opening in side 10 by a coil spring 12. The inner face of ball 11 is provided with an inlet 13 and the outer face forms a projection 14 which extends upwardly and terminates in a trough 15 which extends longitudinally of the journal throughout a substantial portion of the length of the latter, thereby being adapted to supply lubricant over a considerable area.

I prefer to equip my lubricator with waste packing such as is in general use and to support the same I provide a cage 16 of sheet metal, the upper edges of which are adapted to fit the lower portion of the journal 90 to which the lubricator is applied and the bottom of which surrounds barrel 3 and is yieldingly supported by a coil spring 17. Trough 15 is yieldingly maintained against the surface of the journal A by a spring 18 95 here shown as a coil compressed between member 14 and the bottom of cage 16. The side 10 of member 9 is preferably screwed thereinto or otherwise made removable to facilitate the insertion of member 11. Obviously the ball and socket joint provided by this construction enables the trough to follow journal A in every shifting movement of the latter without losing any lubricant which may be present in member 9 or in the trough. The tendency of wear on the edges of the trough is such as to improve their contact with the face of the journal.

A series of overflow holes 19 are provided in the side of trough 15 above the edge of the lower side of the trough. Through these holes lubricant is supplied through the waste

contained in cage 16 and back pressure upon the pump or pump passages is eliminated. By means of this construction the oil or other lubricant is pumped directly to the journal instead of being applied thereto only through waste which may fail to contact with the journal or may become hardened or otherwise ineffective.

With this improved construction, the force hitherto required in pumps for such devices is reduced and I also eliminate the possible failure of a lubricator due to the stoppage of holes in a pipe which delivers oil to the waste, that is, with the direct supply of lubricant to the journal much less work is required of the operating mechanism.

Obviously the details of construction of my lubricator may be varied without departing from the spirit of my invention as expressed in the following claims.

I claim:

1. In a lubricator for railway journal boxes, a lubricant reservoir, a pump including a vertical discharge passage having a circular opening in its side, a hollow ball in said passage seated against the periphery of said opening and provided with an inlet for lubricant in said passage, an L-shaped pipe leading outwardly and upwardly from said ball, a trough extending longitudinally of a journal to be lubricated and connected to said pipe and carried thereby in a position vertically disaligned with said passage with its edges adapted to contact with the journal, and a spring support for said trough.
2. In a journal lubricator, a lubricant reservoir, an element floating in the lubricant contained therein, a pump cylinder which receives fluid from said reservoir, a pump plunger reciprocating in said cylinder, and a connection between said plunger and element whereby movement of the latter relative to said cylinder and produced by inertia of the element will operate said plunger.
3. In a journal lubricator, a lubricant reservoir, an element floating in the lubricant contained therein, a pump cylinder which receives fluid from said reservoir, a pump plunger reciprocating in said cylinder, and a connection between said plunger and element whereby movement of the latter parallel to said cylinder will operate the pump, said connection being constructed to provide for vertical movement of the element relative to said plunger to accommo-

date variations in the height of lubricant in said reservoir.

4. In a journal lubricator, a lubricant reservoir, a block adapted to float in the lubricant in said reservoir and substantially smaller in area than the surface of said lubricant, a pump plunger secured to said block and adapted to be reciprocated by the shifting of said block in the reservoir, and a pump passage through which said plunger forces lubricant to a journal to be lubricated.

5. In a journal lubricator, a lubricant reservoir, a horizontal pump cylinder and plunger near the bottom of said reservoir, an upwardly extending conduit from said pump cylinder near the center of said reservoir, a block surrounding said conduit and adapted to float in lubricant contained in said reservoir, and a rigid connection between said block and said pump plunger whereby inertia produced reciprocal movements of said block will pump lubricant from said cylinder to said conduit.

6. In a journal lubricator, a lubricant reservoir, a pump, a lubricant conduit extending upwardly therefrom towards a journal to be lubricated, and a member floatable on lubricant in said reservoir and surrounding said conduit and movable transversely thereof to operate said pump.

7. In a lubricator for railway journal boxes, a lubricant reservoir, a pump including a vertical discharge passage having an opening in the side thereof, a hollow ball in said passage provided with an inlet for lubricant in said passage, a spring in said passage pressing said ball against the periphery of said opening, a pipe extending horizontally and vertically from said ball and provided with a delivery orifice, and a spring supporting the horizontal portion of said pipe and thrusting said orifice into contact with a journal to be lubricated.

8. In a journal lubricator, a lubricant reservoir, a stationary pump body, a lubricant conduit extending upwardly from said pump body to deliver lubricant to a journal, a pump plunger, and a member surrounding said conduit floatable in lubricant in said reservoir to move transversely of said conduit to operate said plunger.

In testimony whereof I hereunto affix my signature this 6th day of July, 1922.

JAMES J. HENNESSY.
